UNITED STATES PATENT OFFICE.

ALBERT W. SHERWOOD, OF BUFFALO, AND GEORGE B. GROFF, OF EBENEZER, NEW YORK.

COMBINED IRONING BOARD AND STAND.

Application filed December 17, 1923. Serial No. 681,211.

This invention relates to an ironing board, and contemplates the provision of a combined board and stand therefor, the latter being designed to provide a compartment for the board when not in use and thus maintain the board and its covering in a clean condition, the stand being also capable of being folded into a small compact article so that the same can be conveniently moved from place to place and stored in a comparatively small space.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a side elevation showing the ironing board supported upon the stand for use.

Figure 2 is a sectional view taken on the line 2—2 of Figure 1.

Figure 3 is a bottom plan view of the ironing board.

Figure 4 is a top plan view of the holder with the component parts in folded position.

Figure 5 is a sectional view taken on the line 5—5 of Figure 4.

Figure 6 is a sectional view taken on line 6—6 of Figure 4.

Figure 7 is a fragmentary top plan view of the ironing board.

Figure 8 is a sectional view taken on line 8—8 of Figure 7.

Figure 9 is a fragmentary sectional view showing how the board is associated with the end support.

Referring to the drawings in detail 10 indicates an ironing board, and secured to the underside of this board at an appropriate point in its length is a transverse cleat 11 adapted to be used in conjunction with the supporting structure or stand for the board 50 to be hereinafter described. The board is provided with a covering 12 which is secured to the board in any suitable manner, a portion of this covering being received by notches 14 formed in the opposed longitudinal edges of the board to prevent the cover

from slipping. The end of the board is cut-away to accommodate an iron holder 15 which is in the nature of a flanged metallic plate or receptacle, three sides of which are secured to the edges of said cutaway portion in which it is arranged. The remaining side 16 of this iron holder extends a slight distance beyond the end of the board, and is used to assist in supporting the board upon the stand in a manner to be presently set forth. A cross piece 17 is secured to the underside of the board and rises directly beneath the iron holder to support the latter.

The stand for the board includes an elongated body portion 18 of hollow formation, 70 and this body portion has a compartment for the reception of the ironing board when the latter is not in use. The body portion 18 may be constructed in any suitable manner, and as shown consists of a rectangular frame to which the opposed side plates 18' are secured. This holder is of a size to accommodate the board 10, and as clearly shown in Figure 5, the board is adapted to be arranged within the holder when not in use by sliding the board through the open end of the holder. Said open end being preferably that end to which the end member 19 is pivoted and which is operatively disposed at the upper end of the body. The 85 board together with its covering is thus kept in a clean and sanitary condition, the compartment being substantially of the same length as the length of the board. The body portion 18 of the stand is adapted to be arranged at an inclination to the floor or surface when in use, the lower end of the body portion reposes upon said surface as shown in Figure 1. The body portion is supported in this position for use by means of an end member 19 which includes the legs 20 pivoted at their upper ends to one end of the body portion 18 as shown at 20' and are connected by means of the plate 21'. This member 19 is arranged in a substantially 90 vertical position when the stand is in use, and by reason of its pivotal connections 20' with the body portion 18 of the stand it is susceptible of being folded in the direction of said body portion and parallel therewith when not in use. When folded, the legs 20 of the end member lie at the opposed longitudinal edges of the body portion 18.

The upper edge of the end member is provided with a metallic strip 21 which termi- 110

nates in a hook 22, and this hook is adapted to engage the side 16 of the iron holder when the board is arranged upon the stand for use, and thus assists in holding the board horizontally.

The board however, is further supported in a horizontal position for use by means of a bracing member 23 which is pivoted upon the upper side of the body portion 18 and adapted to project obliquely therefrom when the stand is set up for use. When the bracing element is in use, the free edge thereof engages the transverse cleat 11 carried by the underside of the ironing board. The bracing member 23 is provided with spaced cleats 24 upon the lower side of the member 23, the inner ends of which project beyond the member 23 and are bifurcated to receive eye members 25 secured to the upper surface 20 of the body portion 18 of the stand, the eye members in said projections receive a rod 26 on which the bracing member is pivoted. Consequently this bracing member 23 is susceptible of being folded to lie against 25 and parallel with the upper surface of the body member 18 when the stand is not in use. The opposite side edges of the bracing member are secured to parallel links 27 by a hinged joint of which the ends of the rod 26 form the pintles, said links being pivotally connected to the parallel links 28 pivoted upon the legs 20 of the end member 19. The lower end of the brace members 28 are pivotally connected to the leg members 19 as shown at A to permit the folding of legs 30 and braces as shown in Figure 5. The links 27 and 28 are of course arranged in alignment when the stand is set up for use, and it will be noted by reason of this 35 association of the parts that when the hinged joint is broken to allow the stand to be folded, the end member 19 and the bracing member 23 are simultaneously moved in opposite directions to their folded positions 40 to lie parallel with and at opposite sides of the body portion 18. The board 10 is separated from the stand by disengaging the hook 22 from the side wall 16 of the iron holder so that it can be conveniently detached to permit a new cloth or covering to 45 be placed upon the board as the occasion may require. From an inspection of the drawing, it will also be noted that the entire device can be arranged to provide a small 50 compact article which can be conveniently

borne from place to place and also stored in a very small space.

While it is believed that from the foregoing description, the nature and advantages of the invention will be readily apparent, we desire to have it understood that we do not limit ourselves to what is herein shown and described, and that such changes may be resorted to when desired as fall within the scope of what is claimed.

Having thus described the invention, we claim:

1. In combination, an ironing board, a stand therefor, including a hollow body portion forming a compartment for the reception of the board when the latter is not in use, said body portion being adapted to be arranged at an inclination to the floor and having one end supported thereby, an approximately vertical end supporting member pivoted to the other end of the body portion and capable of being folded parallel with the latter, means for interlocking one of the boards with said end member, a bracing member pivoted to the upper side of the body portion and adapted to project at an angle therefrom to engage the under side of the board when the latter is not in use and said bracing member being capable of being folded parallel with said body portion.

2. In combination, an ironing board, a stand therefor including a body portion adapted to be arranged at an inclination to the floor and having one end supported thereby, an approximately vertical end supporting member pivoted on the other end of the body portion and capable of being folded parallel with said body portion, a plate formed with an upstanding flange carried by and arranged at one end of said board, means associated with said end member for interlocking engagement with said flange, a bracing member pivoted on said body portion and adapted to project at an angle therefrom to engage the under side of the free end of the board and assist in supporting the latter horizontally, said bracing member being susceptible of being folded against said body portion and a hinged joint between the end member and said bracing member as and for the purpose specified.

In testimony whereof we affix our signatures.

GEORGE B. GROFF.
ALBERT W. SHERWOOD.
